UNITED STATES PATENT OFFICE.

CHARLES E. BLYTH, OF DUNCHURCH, ENGLAND, ASSIGNOR TO ALFRED HERBERT LTD.,
OF COVENTRY, ENGLAND.

MACHINE FOR THE PRODUCTION OF POWDERED FUEL.

Application filed September 8, 1925. Serial No. 54,913.

This invention relates to pulverizing machines and more particularly to machines of the type shown in the patent to Blyth, No. 1,446,151, dated February 20, 1923. It has been found as the result of experimental studies on the machine shown in the Blyth patent for pulverizing fuel, that if the impact pegs on the casing and the rotor in the second grinding zone are of full length and project substantially the whole distance from the rotor to the casing wall, these pegs set up a centrifugal action in opposition to the exhaust fan which makes it impossible to get enough pulverized fuel through the machine to form a flame. The length of the pegs on the rotor is therefore an important factor in the operation of the machine. It is also found that if the coarse pieces of material should escape from the second pulverizing zone into the fan casing without being broken to a sufficiently fine size, they impose a burden on the fan of subdividing them sufficiently to permit their passing with the fine fuel into the burner, as the heavy particles cannot be blown along with the air unless they are reduced to a very small size. It is therefore necessary, if fine grinding is to be done, that the coarse particles be rejected at the entrance to the fan chamber. In the construction illustrated in my prior patent, two sets of closely arranged fan belts are mounted to revolve with the rotor, one in the inlet zone near the periphery of the disk and the other located in the second zone near the outlet pipe. The blades in the second zone reject coarse particles attempting to pass therethrough but they are not properly located and arranged to scoop the coarse material from the outgoing air current and hurl it back into the path of the revolving pegs satisfactorily and efficiently. The outflow of the air is impeded by these blades and the restricted outlet passage, and the counter air pressure thus set up requires greater effort on the part of the main fan to remove the material from the pulverizing chamber. Since these blades are subjected to severe wear and will have but short lives, it is necessary to shut down the machine frequently for repairs, and the parts are expensive and difficult to replace. For such reasons, the machine described in my prior patent is not commercially practical.

It is accordingly the main object of my invention to overcome these difficulties and improve the machine shown in said patent, and particularly to provide a machine adapted for pulverizing fuel, which will be highly efficient in operation and will have a large capacity and a long life of useful service.

It is a further object of my invention to provide a construction which will serve efficiently to scoop the coarse particles from the air current passing to the outlet and to permit only such finely pulverized material as will travel in a cloudlike formation to pass through the rejector from the pulverizing zone to the fan casing and to throw the coarse particles back into the path of the pegs for further pulverization.

It is a still further object to provide an arrangement of attrition pegs in the second zone which will permit the passage of air, and the finally divided fuel carried thereby, from the first grinding zone to the fan chamber, and yet will serve to grind efficiently the material supplied thereto and particularly to provide such an arrangement that the fuel may be rejected at the outlet and forced to recirculate repeatedly in this second zone until it has been ground to such a fine size that it will pass readily between the rejector arms.

With these and other objects in view as will be apparent in the following disclosure, my invention resides in the combination of parts set forth in the specification and covered by the claims appended hereto.

Referring to the drawings in which like reference numerals indicate like parts:

Fig. 1 is a vertical section partly broken away of that portion of the pulverizer which relates to the present invention;

Fig. 2 is a fragmentary perspective view of a portion of the device;

Fig. 3 is a fragmentary vertical elevation of a part of the rotor showing the passage therethrough for rejected material;

Fig. 4 is a cross section of the part shown in Fig. 3;

Figs. 5 and 6 are front and side elevational views of one of the rejector arms; and

Fig. 7 is a diagrammatic view illustrating the supposed path of travel of the pulverized material.

As will be understood by reference to the prior patent to Blyth, this type of machine comprises a hollow, cylindrical casing 10,

110

within which is rotatably mounted a disk 11 supported on and rotated by a shaft 12 driven by any suitable source of power. The manner of mounting the disk on the shaft 5 may be in accordance with any well known mechanical construction, and I have herein illustrated the rotor as mounted on a sleeve 13 and clamped in position therein by means of an adjustable collar 14. The rotor 11 10 comprises two plates 15 and 16, as shown particularly in Fig. 4, and a set of attrition pegs 18 and 19 are mounted on opposite sides of these plates in any suitable manner. In the present instance, the pegs are provided 15 with enlarged heads which are clamped between the plates 15 and 16. Similarly two sets of pegs 20 and 21 are mounted on the opposite side walls of the casing 10, the pegs 20 interfitting with the pegs 18 and pegs 21 20 on the opposite wall of the casing interfitting with the pegs 19, these various sets of pegs being so located that the pegs on the rotor may pass between the pegs on the casing wall and pulverize material by impact 25 therebetween.

Material is fed into the machine through a hopper 25 and into the passage 26 and thence centrally into the chamber on the left hand side of the rotor shown in Fig. 1. The material is broken by impact between the pegs 18 and 20 and due to the suction of the fan 28 which is adjacent the exit 29 of the casing, the material tends to travel from this chamber around the annual portion of the rotor 30 into the second chamber formed between the rotor and the right hand wall of the casing. Air is admitted into the pulverizing chamber through the passages 31 and 32.

I find it desirable to provide a device 40 which will reject any over-sized material which would otherwise escape through the exit 29 and insure its retention in the pulverizing chamber until it is ground to the desired degree of fineness. One simple construction for accomplishing this purpose 45 comprises a set of rejector arms 35 mounted on the sleeve 13 to rotate with the shaft 12 and located outside of the grinding zone close to the exit 29. These arms are preferably 50 disposed substantially radially to the shaft and are so shaped that they automatically scoop all coarse material from the air current and throw it back into the grinding zone.

While these rejector arms may be made in 55 various shapes and arrangements, I have shown them herein as having forwardly facing concave surfaces formed of hollow pieces of pipe which are cut away and bent as shown particularly in Figs. 2, 5 and 6, to 60 form U-shaped troughs 36 which serve to scoop the material from the air current and hurl it centrifugally out of the open end of the trough. These rejector arms are located close to the exit orifice 29 of the pulverizer 65 casing so that they will not be in the field of pulverizing action and will not limit the operation of the pegs. The arms are preferably threaded at their lower ends 38 and screwed into corresponding pockets in a split collar 37 and held in place by lock nuts 39. 70 The arms extend all the way across the exit opening 29 and close to a ring 40 which is fastened to the wall 41 of the casing. 75 The arms are arranged with the hollow U-shaped portions 36 facing in the direction of revolution of the arms. The arms are bent backwards slightly, as indicated by the curve 42 in Fig. 6, and the ring 40 is beveled off as shown particularly in Fig. 2 so that material striking this ring will be given a glancing blow and thrown back into the grinding zone. 80 These rapidly rotating arms therefore form a screen through which the slowly moving solid particles cannot pass, but which lets a cloud of fine material pass between the arms into the fan chamber. The coarse material is thrown outwardly against the rotor or in the path of the pegs in the grinding zone and are thus returned by centrifugal action toward the outer portion of the casing where they are effectively ground before 85 they can get back towards the exit. 90

In certain instances, I may utilize a feature illustrated in the drawings, which, however, may be omitted if desired. This comprises a series of perforations 50 and 51 in the two plates 15 and 16 of the rotor, which are so located that material thrown by a glancing blow against the ring 40 is deflected along the line c—c in Fig. 7 and much 100 of it will pass outwardly through the openings 50 and 51 of the rotor into the chamber of the first effect where the coarser material is initially ground. In order to assist in this action and at the same time help to prevent material in the first chamber from passing through these openings into the second chamber without being ground, I preferably 105 form the walls of the openings 50 and 51 of a flaring shape as illustrated particularly in 110 Figs. 3 and 4. The flared portions 53 of these openings serve as vanes which tend to deflect material striking against the surfaces and thrust it back into the same grinding zone. It is also possible that these passages 115 through the rotor serve to equalize the air pressure within the casing and admit directly into the chamber of the second effect a cloud of fine material which has been sufficiently pulverized in the chamber of the first 120 effect, thus short-circuiting some of the air through the rotor and counteracting the centrifugal force which tends to pass all of the material around the outer edge of the rotor.

In the first grinding zone, the tendency of the rotating pegs is to move the material outwardly toward the periphery of the disk and thus aid the fan in drawing the material through the casing, whereas in the second zone the rotating pegs tend to counteract the 125 130

suction effect of the fan and prevent material passing toward the exit 29. If the pegs 19 on the rotor project substantially the whole distance across this space to the casing 5 wall, then there is very little opportunity for material to pass between these pegs towards the exit against the centrifugal force set up by the rotating pegs. Moreover, there should be a passage provided whereby air 10 carrying material sufficiently fine in size may pass directly to the fan chamber without being subjected to the grinding effect of the pegs 19. It will be understood that these pegs, in constantly striking the material as 15 it passes through the casing and in setting up eddy currents in the air, increase enormously the power consumption of the machine and it is highly desirable to minimize this power loss and increase the rapidity 20 with which the material may pass through the second grinding zone.

I find that by making the pegs 19 quite short and by having the pegs 21 long and interfitting between the separate rows of pegs 19, I produce a much better grinding 25 effect than heretofore obtainable. As illustrated, the pegs 19 project not more than half way across the space between the rotor and the casing, while pegs 21 project substantially the full distance. While the theoretical 30 considerations underlying this construction are not well understood, it is thought that the passage of the air and fuel is somewhat as illustrated in Fig. 7. As indicated 35 by the various lines and arrows, the fuel is supposed to pass along the solid line *a—a* from the first grinding zone around the periphery of the rotor 11, then adjacent the casing wall between the pegs 21, then bending 40 around the ring 40 it turns between the radial rejectors 35 and escapes to the fan chamber. Various secondary eddy currents may be formed by the different sets of revolving pegs, but such recirculation is perhaps of 45 minor importance. The coarse material which reaches the rejector blades 35 is hurled back along the line *c—c* against the deflector ring 40, then towards the rotor and into the path of the rotating pegs 19. This material 50 then passes under the centrifugal action of the pegs 19 outwardly between the revolving and stationary pegs and is again reground, after which it joins the air current indicated by the line *a—a*. The material 55 which is sufficiently fine to be borne by the air in a cloudlike formation will pass between the radial arms 35, while such material as is heavy enough to be thrown outwardly by the centrifugal action of the 60 blades will be hurled back into the grinding zone.

If it is desired to grind material to a coarser extent, the radial arms may be removed or so modified as not to throw back 65 fine material in the grinding zone, in which

case one depends upon the recirculation caused by the eddy currents to insure grinding the material to a sufficiently fine degree.

It is preferred that the pegs 21 project substantially all the way to the rotor since 70 with a shorter peg there is a tendency for the air current passing outwardly through the rotating pegs and the air passing inwardly through the stationary pegs to gyrate and thus cause congestion in the machine. It 75 may also be observed that the holes through the rotor are intended primarily to prevent congestion in the chamber of the second effect. The rejector arms tend to return a considerable amount of coarse material into 80 the grinding area of the second chamber and these holes through the rotor make it possible for some of the material thus crowded in the second chamber to escape into the first grinding zone. By making the sides 85 of the holes of fanlike shape, these surfaces act somewhat as fans and tend to draw the air back through the holes into the first chamber and thus cause a positive recirculation of the coarser particles of the fuel. It 90 will also be understood that the rejector blades scoop the dust cloud while the cloud is traveling at a comparatively low velocity, and since the rejector arms move rapidly 95 across the path of the particles they are sure to strike the major portion of them. If a particle is heavy enough to be caught by the rejector blades, it will be retained in the U-shaped portion of the blade and thrown centrifugally outwardly into the grinding zone. 100

Having thus described my invention, what I claim and desire to secure by Letters Patent is:

1. A pulverizing apparatus comprising a casing having a centrally located outlet, 105 impact members mounted to revolve substantially concentrically with the outlet, means for introducing air and material to be pulverized to the peripheral zone surrounding the impact members, means to move the air and pulverized material inwardly towards the outlet and rejector arms revoluble across the outlet and arranged to scoop coarse particles from the outgoing air and hurl them back into contact with said impact 110 members. 115

2. A pulverizing machine comprising a casing having a centrally located outlet, a rotor mounted therein to revolve concentric with said outlet, impact members on said 120 casing and rotor arranged to pulverize material by impact thereagainst, means for feeding air and material to be pulverized to the peripheral zone surrounding said members, means to move the air from said zone towards said outlet, and substantially radial rejector arms mounted to rotate close to said outlet and scoop the coarse material from the 125 cloud of suspended finely divided material which is drawn towards the outlet and to 130

hurl the same into the path of the impact members.

3. A fuel pulverizing machine comprising a casing having a fuel and air entrance, a rotor mounted therein, impact pegs on said casing and rotor arranged to pulverize the fuel by impact thereagainst, a deflecting ring on the casing defining an exit for the pulverized fuel mixed with said air, and spaced radial rejector arms mounted to revolve close to said ring which have forwardly facing surfaces shaped and arranged to throw the coarse material against said ring and into the pulverizing chamber but permit the passage of a cloud of air and finely divided material between said arms.

4. A pulverizing machine comprising a casing having an entrance and an exit for air and the fuel on opposite sides thereof, a shaft rotatably mounted in the casing, a rotor fixed to said shaft, cooperating impact members on both sides of said casing and rotor arranged to form two communicating pulverizing zones, and a series of rejector arms mounted on said shaft close to the exit in the second zone and arranged to revolve with the rotor and prevent the passage of coarse fuel through the exit, said rotor having openings therethrough so located and shaped that coarse material thrown by said rejector arms may be returned to the first grinding zone.

5. A pulverizing machine comprising a casing having an inlet and a centrally located outlet for air and the material to be pulverized, means in the casing to pulverize said material and revoluble radial rejector arms adjacent the outlet which have forwardly facing concave surfaces arranged to scoop coarse particles from the air current and hurl them centrifugally into the pulverizing zone.

6. A pulverizing apparatus comprising a

casing having opposed internal walls and an inlet and a centrally located outlet opening on opposite sides thereof for air and the material to be pulverized, a rotor disk mounted between said openings and spaced peripherally from the casing to provide two communicating pulverizing zones, means to pulverize the material in both zones including a set of beater pegs on the disk interfitting with a set of pegs on the casing wall in the second zone, all of the pegs on the disk in the second zone being relatively short and spaced a considerable distance from the casing wall and the pegs on the casing wall projecting between the pegs on the disk substantially to the rotor, whereby the material may be pulverized between the two sets of pegs adjacent to the disk and air and the pulverized material may pass freely adjacent the casing wall from the periphery of the casing towards the exit.

7. A pulverizing machine comprising a casing having an inlet on one side and a centrally located outlet on the other, a rotor disk between said openings, means cooperating therewith to form first and second grinding zones communicating at the periphery of the disk, including a set of short pegs on the disk interfitting with a set of pegs on the casing in the second zone arranged to pulverize material adjacent the disk and provide a free passage adjacent the casing for the air to pass from the first zone to the outlet and a rejector arm located outside of the grinding zone and revoluble across the entire outlet which is arranged to return coarse material into the path of the revolving pegs.

Signed at the city of Coventry, England this twentieth day of August 1925.

CHARLES E. BLYTH.
